UNITED STATES PATENT OFFICE.

JACOB T. LANDGRAF, OF MACOMB, ILLINOIS, ASSIGNOR TO AMERICAN STEEL PRODUCTS CO., OF MACOMB, ILLINOIS, A CORPORATION OF ILLINOIS.

HOODED BROODER STOVE.

Application filed May 27, 1927. Serial No. 194,582.

My invention relates to brooders of the general type in which a heater, such as a slow-burning coal stove, has its major portion surrounded by a hood or hover which 5 extends to within a relatively short distance from the floor on which the heater seats.

In brooders of this type, it has long been customary to provide the top of the hover with an opening of sufficient size to permit 10 fuel to be fed into the heater without raising the hover. However, access must also be provided to the base portion of the stove for removing the ashes from the ash-pit. For this latter purpose, two arrangements have 15 heretofore been customary. One consists in the providing of a rope and pulley arrangement for raising the hover, thereby requiring a considerable addition to the first cost and considerable labor in installing the 20 hoisting equipment. The other consists in making a door or other part of the hover movable, which also adds materially to the cost and which usually requires the providing of increased rigidity in the hover parts 25 which remain stationary. Moreover, the movable doors or flaps as provided for this purpose usually afford rather restricted access to the base of the heater, thus making it difficult to clean the floor around the heater. 30 My present invention aims to provide a brooder in which the hover can readily be tilted bodily so as to afford free access to the ash-pit and to the floor around the heater, while still insuring a rigid supporting of 35 the hover when the latter is in its normal position. It also provides simple means for releasably holding the hover in its tilted and access-affording position, and provides a heater and hover combination which will be 40 simple and easy of construction.

Furthermore, my invention provides a brooder in which the hover is firmly supported from the top of the heater when the hover is in its normal position, in which the 45 hover can readily be rocked with respect to the heater about a predetermined axis located so that the tilting of the hover will afford ready access to the ash-pit of the heater, and in which the latching means are 50 arranged for ready engagement with the hover when the latter is rocked about the said axis.

Moreover, my invention provides a brooder in which simple formations on the hover 55 and the heater co-operate for affording this

rocking or tilting of the hover without requiring auxiliary hinge parts, thereby also permitting the hover to be placed upon or removed from the heater without the use of tools. It also provides an arrangement in 60 which the usual flue pipe of the heater can serve as a support for a part of the latching means, and in which the hover (when in its normal position) permits a ready opening of a horizontally swinging fuel door. 65

Still further and also more detailed objects will appear from the following specification and from the accompanying drawings, in which

Fig. 1 is an elevation of a brooder embodying my invention, showing this with the hover in its normal position. 70

Fig. 2 is a perspective view of the same brooder, with the hover held in its tilted position to afford access to the ash-pit and 75 the floor adjacent to the heater.

Fig. 3 is an enlarged and fragmentary vertical section through a portion of the hover collar and the adjacent upper parts of the heater, taken along the line 3-3 of 80 Fig. 4.

Fig. 4 is an enlarged plan view of the heater and the canopy top of the hover, with portions of the said canopy top broken away.

Fig. 5 is an enlarged side elevation of the 85 upper portion of the heater, with an upper portion of the tilted hover shown in section.

Fig. 6 is a view similar to a portion of Fig. 5, but with the hover in its normal or 90 untilted position.

In the drawings, I am showing my invention as applied to a brooder heater of the type disclosed in the Gaddis Patent No. 1,567,364 entitled Brooder stove, although I do not wish to be limited to the employment 95 of my invention in connection with any particular type of heater. In this Gaddis type of slow-burning coal heater, the heater body 1 is surmounted by a top casting 2 which has an annular ledge 3 extending laterally 100 beyond taller portions of this casting. The top casting 2 is partly cut away to afford a fuel inlet which is normally closed by a horizontally swinging door 4, which door is disposed somewhat above the top of the 105 ledge 3, as shown in Fig. 3. The top casting 2 also has an upwardly directed collar 5 upon which the usual flue pipe 6 is socketed, and the body of the stove has the usual ash-pit door 7 near its bottom. 110

The hover of the brooder has as its major portion a downwardly flaring frustro-conical hood which has its upper end larger in diameter than the said ledge 3 of the top casting, this hood being desirably made of radial sheet metal sections 8 secured to each other by bolts 9. The top of the hood composed of these assembled sections underhangs, and is secured by bolts 10 to a downwardly flaring peripheral flange 11 on the canopy top of the hover, which canopy top also includes a top plate 12 connected by a tubular riser portion 13' to the bore of the flange 11. This top plate and the bore of the tubular riser portion are desirably considerably larger in diameter than the upper portion of the heater, and the perforation 13 in the top plate 12 is so disposed as to space the flange 11 considerably from the top of the heater at the side of the heater which is above the ash-pit door 7. The perforation 13 is desirably so shaped that it will approximately fit over the stove top portions which project upwardly beyond the top of the ledge 3, as shown in Fig. 4.

To afford ready access to the ash-pit, I provide means which serve as a hinging connection between the heater and the hover, so as to permit the hover to be tilted by rocking it about the top of the heater on an axis parallel to the ash-pit door 7 and at the opposite side of the heater from that door. This hinging connection is preferably arranged so that its co-acting portions are assembled by merely setting the hover down over the heater, without requiring the use of any tools. For that purpose, I am here showing the ledge 3 as provided with a pair of circumferentially spaced and upwardly projecting lugs 14, each of which is outward of the main portion of the ledge 3 and each of which lugs extends through a perforation 15 in the top plate 12 of the hover canopy. The lugs 14 have their axes in a plane approximately parallel to the upper edge of the ash-pit door 7 and each perforation 15 is desirably elongated at right angles to the said plane, so as to clear the adjacent lug 14 when the canopy top of the hood is tilted as shown in Fig. 5. During this tilting, the inner edges of the perforations 15 engage the inner edges of the said lugs, and with the lugs close to the outer edge of the ledge 3 and overhanging the body of the heater, the elongation of each perforation will readily permit the canopy top to be tilted considerably further than shown in Fig. 5, or to the extent illustrated in Fig. 1.

Then I provide means for holding the hover in such a tilted position, as by hinging a hook 16 at its upper end to a strap 17 clamped to the flue pipe 6, and by providing the canopy top with a perforation 18 disposed for receiving the hook end of the said hook, this perforation being desirably

in the tubular riser portion 13' as shown in Fig. 3. With the hover thus releasably held in its tilted position, it will be obvious from Fig. 1 that the user has ready access to the ash-pit door 7 for removing the ashes, and that he also is able to sweep the floor entirely around the heater so as to keep this floor in a sanitary condition. As soon as the hook is unsnapped, gravity returns the hover to its normal and axially vertical position of Fig. 1, in which the overlapping of the ledge 3 by parts of the canopy top plate 12 effectively closes the top of the hover, so as to afford an upwardly closed brooder chamber around the major portion 80 of the heater.

By constructing my brooder as above described, I can ship the hood sections 3 in a flat form to reduce the packing space, as the hover can readily be assembled by any one who can handle a screw driver. Then the mere setting of the hover down on the heater with the perforations 15 slipped over the lugs 14 places the hover in its operative position in which it can instantly be tilted by rocking it upon the heater top edge adjacent to these lugs. During this rocking, the hover is continuously supported by the heater, so that the effort required for tilting the hover is much less than would be needed for bodily lifting a hover in the previously customary manner, thereby enabling even a child to care for a coal-burning brooder stove embodying my invention.

However, while I have heretofore described my invention in an embodiment including a sectional hood, pivoting lugs overhanging an edge of the top casting, and pivoting formations in the top plate of the hover canopy, I do not wish to be limited to these or other details of the construction and arrangement thus described, as many changes might obviously be made without departing either from the spirit of my invention or from the appended claims.

I claim as my invention:

1. A brooder comprising a heater, and a hover having a top plate normally seated on edge portions of the heater top, the said top plate and heater top having interengaging formations affording a hinging connection on a predetermined horizontal axis to permit the hover to be tilted with respect to the heater, the said formations being disposed to permit the hover to be lifted freely off the heater and to be interengaged when the hover is set down over the heater.

2. A brooder comprising: a heater having a substantially flat top and a pivoting projection both extending above an annular ledge; and a hover having a top provided with a perforation substantially fitting the said top portion to center the hover with respect to the heater, the hover top being normally seated on the said ledge and also hav-

ing a pivoting formation disposed for engaging the pivoting projection so that the hover can be tilted by rocking the same about the engagement of the pivoting formation 5 with the pivoting projection.

3. A brooder comprising: a heater having in its upper portion a flat topped ledge and a top part surmounting and surrounded by the said ledge; a hover having a flat top per- 10 forated to slidably fit down over the said top part of the heater, the part of the flat top adjacent to its said perforation seating normally on the said ledge; and means spaced from the said top part of the heater for 15 hingedly connecting the said top of the hover to the heater on a definitely positioned horizontal axis to permit a tilting of the hover with respect to the heater.

4. A brooder as per claim 3, in which the 20 said hinging means are arranged to permit the hover to be raised bodily off the heater.

5. A brooder comprising a heater having a fuel door in its top and a flue duct projecting upwardly beyond its top; a hover 25 including a top, and a hood suspended from the top and freely housing the heater; the hover top having a perforation formed to clear the said fuel door and flue duct when the hover is lowered over the heater, and the 30 hover top having portions radially outward of the said perforation adapted to seat on the top of the heater; the hover top and heater having formations adjacent to the flue duct and interengaged by the lowering of the 35 hover over the heater and serving as a hinging connection to permit the hover to be tilted about the top of the heater.

6. A brooder comprising: a heater; a hover including a canopy top and a hood 40 suspended from the canopy top; the canopy top including a top plate normally resting upon and extending laterally beyond the top of the heater, a peripheral flange depending from the edge of the top plate, to which 45 flange the hood is secured; the hover and the heater top provided with interengaging means affording a hinging connection to permit the hover to be tilted with respect to the heater; and releasable means interposed be- 50 tween the heater and the said flange of the canopy top for holding the hover in a tilted position.

7. A brooder comprising: a heater having a fuel door in its top and having a ledge 55 extending laterally below the fuel door, a hover including a perforated canopy top nor-

mally seated on the said ledge, and a hood suspended from the said canopy top, the canopy top also having another perforation and the heater having an upwardly directed 60 extension projecting loosely through the last named perforation to co-operate with the wall of that perforation for affording a hinging connection to permit the collar and hover to be tilted with respect to the heater. 65

8. A brooder comprising: a heater having a fuel door in its top and having a ledge extending laterally outward of the heater below the fuel door, a hover including a per- 70 forated top normally seated on the said ledge and a hood suspended from the said top, the heater having a pair of upwardly directed projections spaced circumferentially of the heater, and the said hover top having a pair of perforations through which the 75 projections respectively extend, the said projections being adjacent to an edge of the top of the heater and disposed so as to co-operate with the perforations for permitting the hover hood to be rocked upon the heater. 80

9. A brooder comprising: a heater having an annular ledge near its top; a hover including a flat annular top normally seated upon and extending laterally beyond the ledge, a downwardly directed peripheral 85 flange on the said hover top, and a downwardly flaring hood secured at its upper end to the said flange; the heater having an upwardly directed projection at an edge of its top portion, and the said hover top having 90 a perforation spaced inwardly from its flange and partly housing the said projection, whereby the said projection co-acts with the wall of the said perforation to permit the collar to be rocked about the said 95 heater edge portion for tilting the hood.

10. A brooder comprising a heater having a pair of circumferentially spaced upward projections adjacent to its upper edge, and a hover having an annular top normally 100 seated on the top of the heater, the said annular hover top having a pair of perforations through which the said projections extend when the hover is seated on the heater, the inner wall portions of the perforations 105 cooperating with the projections to afford a hinging connection between the heater and the hover for tilting the hover.

Signed at Macomb, Illinois, May 24th, 1927.

JACOB T. LANDGRAF.
